Primary Examiner — Joseph Kukella*Assistant Examiner* — Lavon M. Amerson(74) *Attorney, Agent, or Firm* — Murray, Ziel & Johnston; Aaron Powell(57) **CLAIM**

The ornamental design for a vehicle side step, as shown and described.

DESCRIPTION

FIG. 1 is a top, front, right side perspective view of a vehicle side step, showing my new design;

FIG. 2 is a bottom, rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2; and,

FIG. 11 is an enlarged view of portion 11 in FIG. 5.

The evenly dashed broken lines illustrate portions of the vehicle side step and form no part of the claimed design. The unevenly dashed broken lines define the boundaries of enlarged views and form no part of the claimed design.
